US00D960628S

(12) **United States Design Patent** (10) Patent No.: **US D960,628 S**
(45) Date of Patent: **** Aug. 16, 2022**

(54) **TOASTER**

(71) Applicant: **MIDEA GROUP CO., LTD.**,
Guangdong (CN)
(72) Inventors: **Jeongmin Jo**, Guangdong (CN); **Ying
Song**, Guangdong (CN)
(73) Assignee: **MIDEA GROUP CO., LTD.**,
Guangdong (CN)

(**) Term: **15 Years**

(21) Appl. No.: **35/511,063**

(22) Filed: **Oct. 12, 2020**

(80) **Hague Agreement Data**

Int. Filing Date: **Oct. 12, 2020**

Int. Reg. No.: **DM/211888**

Int. Reg. Date: **Oct. 12, 2020**

Int. Reg. Pub. Date: **Jan. 1, 2021**

(30) **Foreign Application Priority Data**

Jun. 12, 2020 (CN) 202030300428.4

(51) LOC (13) Cl. **07-02**

(52) **U.S. Cl.**

USPC **D7/330**

CPC **A47J 37/00** (2013.01)

(58) **Field of Classification Search**

USPC D7/323, 328-330, 390, 354; D23/323,

Primary Examiner — Richard E Chilcot

(57) **CLAIM**

The ornamental design for a toaster, as shown and described.

DESCRIPTION

2. Toaster
- 2.1 Front
- 2.2 Back
- 2.3 Left
- 2.4 Right
- 2.5 Top
- 2.6 Bottom
- 2.7 Perspective

1 Claim, 7 Drawing Sheets
